UNITED STATES PATENT OFFICE.

THOMAS A. HUGHES, OF CHICAGO, ILLINOIS, ASSIGNOR TO WOLFF MANUFACTURING CORPORATION, OF CHICAGO, ILLINOIS, A CORPORATION OF ILLINOIS.

SAND MOLD.

Application filed September 28, 1923. Serial No. 665,264.

To all whom it may concern:

Be it known that I, THOMAS A. HUGHES, a citizen of the United States, residing in Chicago, in the county of Cook and State of Illinois, have invented a new and useful Improvement in Sand Molds, of which the following is a specification.

This invention relates to the art of molding, and has more particular reference to the art of forming molds wherein the mold parts, because of the shape of the article, have in the past required an angular draw and assemblage to provide the necessary clearance for separation and assemblage.

15 An example of such an article is an apron bath tub wherein a vertically arranged integral apron extends from the rim of the tub to the floor and is waved across the height of the apron to improve the appearance.

The particular embodiment of the invention hereinafter described, for the purposes of illustration, relates to such a tub, but it will be manifest that the invention has other 20 and general application.

Because of the general vertical arrangement of the apron, the waving of it, of necessity, disposes parts of both the inner and outer faces upon both sides of the vertical and a tilting of the tub is required to permit the drawing of the sand molds where flasks are used, in accordance with the usual practice prior to my invention. The apron in tubs of this character provided for corner 30 installation extends around the exposed corner of the tub and this has required tilting of the flask parts at an angle to the vertical in two directions as will be readily understood. My invention contemplates the separation of certain mold parts or walls to render this angular draw unnecessary, particularly where the walls define outer faces of the sand body, although it will be manifest that by modification similar provision 40 could be provided for the walls having internal surface forming function.

The invention has for its principal object the accomplishment of this result in the molding of bath tubs and other articles, in simple, practical, effective fashion.

Numerous other objects and advantages of the invention will be apparent as it is better understood from the following description, which, when taken in connection with the

accompanying drawings, discloses a preferred embodiment thereof.

On the drawings,

Figure 1 is a top plan view of the cope pattern for a bath tub, in which my present invention is embodied;

Fig. 2 is a longitudinal vertical sectional view through the same, showing the tub body pattern in place;

Fig. 3 is an end view thereof looking from the right in Fig. 1;

Fig. 4 is a partial side view, looking from the bottom of Fig. 1; and

Fig. 5 is a side elevation of the cope and drag.

The cope pattern shown on the drawing 70 comprises a main body 11 in which is positioned a reversible tub body pattern portion 12. The main body consists of two side portions 13 and 14, and two end portions 15 and 16, all integral. Central webs 17 and 18 75 are cast with the body as are also six I-beam wrapping blocks 19. The pattern of the drawings is for the construction of an apron tub for a left hand corner and two walls 21 and 22 are provided to extend up and form 80 the outer faces of the sand mold which, when assembled with the drag, produce the inner surface of the apron at the end and side. The contour, or waving, of this apron can be observed in Figs. 2 and 4, as indicated at *a*. 85 It will be noted that the molded sand between the tub portion 12 and the wall *a* cannot be drawn vertically upward viewing these figures, while the parts are arranged as shown. I have provided for the outward 90 removal of the walls 21 and 22 from sand forming position to permit this vertical draw.

At the bottom of the wall 21, two brackets 23 and 24 extend in beneath the bottom of the pattern and pivotally engage a shaft 25, mounted in bearings 26 and 27 extending down from the underside of the pattern. Three similar brackets 28, 29 and 31 extend in from the wall 22 beneath the pattern and similarly engage a shaft 32 carried in similar bearings 33, 34 and 35. Since the apron extends around the corner *b*, the adjacent ends of the walls are curved and brought into close arrangement at 36 and the shafts 25 and 32 are spaced in from the sides of the flask at their adjacent ends to give an angular swing to the wall away from the

formed sand mold. Wedge lugs 37 and 38 and 39 are provided to receive wedge clamps and hold the walls in operative position. A wedge lug 38 and a wedge lug 39 are mounted respectively on upstanding posts 41 and 42, secured at their bottom to the pattern body.

Means are provided for controlling the opening movement of the walls 21 and 22. 10 These means comprise screw shafts 43 and 44 rotatably mounted in lugs 45 and 46 upon the outer ends of the walls 21 and 22 and threadedly engaged in lugs 47 and 48 on the posts 42 and 41, the lugs 45, 46, 47, and 15 48 being swiveled.

Reference character 60 indicates the cope proper and it will be noted that this cope is provided with two side lugs 61 and 62 adapted to register with side lugs 63 and 64 on the body of the pattern. The lugs 63 and 64 have holes 65 to receive registering pins 66 and, since the cope is to be drawn off the pattern in a vertical direction, these pins extend vertically and through holes 67 vertically disposed through the cope lugs 61 and 62. The cope, in the present instance, is adapted for angular assembly on the drag and to be centered thereon through the utilization of similar pins. It will be manifest that these pins of the drag must present an angular arrangement with respect to the cope in assembly and accordingly angular openings 68 are provided in the lugs 61 and 62 to receive the drag pins thus presented.

In operation, the sand is compressed between the pattern body 12 and the walls 21 and 22 when the latter are clamped in the position shown in the drawings. Said walls are then swung away, the screw shafts 43 and 44 being turned to allow said walls to be moved a sufficient distance to permit vertical draw of the mold. The cope proper 60 may also be vertically drawn and is adapted, by reason of the angular openings 68, to be angularly assembled with the drag in much the same manner as that disclosed in my copending application Serial No. 665, 263, filed September 28, 1923.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

60 I claim:

1. A flask member for use in forming sand molds having one or more outer walls formed to give a shape to the sand body rendering difficult vertical draw thereof, said one or more outer walls being mounted

for movement away from said sand body prior to the drawing operation.

2. A flask member for use in forming sand molds having one or more outer walls formed to give a shape to the sand body 70 rendering difficult vertical draw thereof, said one or more outer walls having an independent lateral movement away from the sand face or faces formed thereby.

3. A flask pattern for use in forming 75 molds requiring ordinarily an angular draw and having sand face defining walls movable laterally away from the sand faces formed thereby to permit vertical draw.

4. A flask pattern for use in forming 80 molds requiring ordinarily an angular draw and having a sand face defining wall movable laterally away from the sand face formed thereby to permit vertical draw.

5. A flask pattern for use in forming 85 molds for bath tubs having vertical aprons waved transversely, comprising an apron face-defining wall removable from face-forming position to permit vertical draw.

6. A flask pattern for use in forming 90 molds for bath tubs having vertical aprons waved transversely and extending about two adjacent sides, comprising walls defining the faces of said aprons, each of said walls being removable from face-forming position 95 to permit vertical draw.

7. A mold member adapted to form the interior face determining surface of a sand body, the wall determining a said face being 100 movable away therefrom to facilitate the vertical draw of the sand body.

8. A mold member adapted to form the interior face determining surface of a sand body, the wall determining said face being 105 movable about a pivoted axis beneath said face to facilitate vertical draw of the sand body.

9. A mold member adapted to form the interior face determining surface of a sand body, the wall determining said face being 110 movable about a pivotal axis out of parallelism with the plane of said wall to facilitate vertical draw of the sand body.

10. A mold member having sand face-determining walls extending around a rounded corner and individually movable away from said face to facilitate vertical draw of the sand body.

11. A mold member having sand face-determining walls extending around a rounded corner and individually movable away from said face to facilitate vertical draw of the sand body, and means detachably securing adjacent ends of said walls when in operative position.

12. A mold member, comprising a sand face-determining wall movable away from a sand face formed thereby to facilitate vertical draw, and means for controlling the movement of said wall.

13. A mold member adapted to form adjacent side wall faces of a sand body, the wall forming members being movable from said sand body and each other upon an obtuse angle.

14. A mold member adapted to form adjacent side wall faces of a sand body, the wall forming members being movable away from the sand faces formed thereby, means detachably securing said walls together at adjacent ends, and means controlling the movement of each wall.

15. A flask member adapted to form adjacent side wall faces of a sand body, the walls being movable away from the sand faces formed thereby, means detachably se-

curing said walls together at adjacent ends, and means controlling the movement of each wall located at the other ends of said walls.

16. A cope and cope pattern for use in forming a sand mold requiring normally angular assembly with a companion drag, said pattern being adapted to permit vertical draw, and guiding means for guiding the cope vertically off the pattern and adapted to guide the cope angularly onto a drag.

17. A cope member adapted to receive and be freed from vertical arranged guide pins of its pattern, and having receiving means for engaging and assembling upon angularly arranged guide pins of its drag.

THOMAS A. HUGHES.
